HEEL UNIT OF A SKI SAFETY BINDING

Masahiro Murata, Tokyo-to, Japan, assignor to
Hope Kabushiki Kaisha

Filed Nov. 5, 1973, Ser. No. 412,984

Claims priority, application Japan May 6, 1973

Term of patent 14 years

Int. Cl. D21—02

U.S. Cl. D34—14 D

FIG. 1

FIG. 2

FIG.3

FIG.4

FIG.5

FIG. 1 is a front elevational view of a heel unit of a ski safety binding showing my new design;

FIG. 2 is a rear elevational view thereof;

FIG. 3 is a top side elevational view thereof;

FIG. 4 is a bottom side elevational view thereof; and

FIG. 5 is a right side elevational view thereof.

I claim:

The ornamental design for a heel unit of a ski safety binding, as shown.
